DISPENSING SYSTEM FOR LIQUEFIED GASES

T. H. Duff, Dallas, Tex.

Application March 22, 1945, Serial No. 584,162

9 Claims. (Cl. 62—1)

1

This invention relates to new and useful improvements in dispensing systems for liquefied gases, and is particularly adapted for use with hydrocarbon gases of the types of butane, propane, and the like.

One object of the invention is to provide an improved system for controlling the vaporization and flow of gas from a liquefied gas storage system.

An important object of the invention is to provide novel means for controlling the flow of vaporized gas from a liquefied gas storage tank to the service outlet of the system.

A particular object of the invention is to provide, in a device of the character described, means for utilizing liquid columns to perform a valving function between the stored gas and a vaporizing and dispensing chamber.

A further object of the invention is to provide improved means for controlling the level of liquefied gas which is permitted to enter the vaporizing chamber in a device of the character described.

Still another object of the invention is to provide, in a system of the type described, means for charging and for maintaining a charge of liquid in that portion of the system providing liquid seal separation between the storage tank and the vaporizing and dispensing chamber.

A still further object of the invention is to provide means for withdrawing liquefied gas from the principal storage space of such a system, conducting such liquefied gas into a vaporizing section of the system and there vaporizing the gas and sending it to a service outlet in substantially the same mixture in which the liquefied gas is present in the storage space, thereby providing a supply of substantially uniform vaporized gas.

A still further object of the invention is to provide means for reoffering low volatile or "rich" gases to the vaporizing and dispensing chamber during periods of considerable temperature differential between the vaporizing chamber and the service lines, whereby such "rich" gases are not forced into the service lines at a time when they would be likely to return to liquid form therein, and yet provide for a reoffering of such gases until temperature conditions are more suitable for their acceptance in the service line in a gaseous state.

Still another important object of the invention is to provide a liquefied gas storage and dispensing system having means for controlling the vaporization and flow of vaporized gas, which means is valveless and free of mechanical parts or mechanisms.

2

Another object of the invention is to provide in such a system means for substantially precluding contact of the stored liquefied gas with parts of the system that may absorb heat incidental to and as a result of the application of heat for vaporizing purposes.

A further important object of the invention is to provide a control system for a liquefied gas storage and dispensing system particularly adapted to be assembled as a prefabricated compact component of a complete system and which may be readily transported to other places for attachment to suitable storage vessels.

Still other objects of the invention are to provide a system which is economical to manufacture, simple in structure and operation, well suited to operation above ground and offering a practical system for use of flame or other applied heat to cause vaporization, and, particularly, a system suitable for complete enclosure without fear of mechanical failure or high maintenance cost.

Additional objects and advantages of the invention will be apparent from a reading of the following description of devices constructed in accordance with the invention, and reference to the accompanying drawings thereof, wherein:

Figure 1 is a view, partly in elevation and partly in section, of a device constructed in accordance with the invention, and showing the same in normal operating position.

Figure 2 is a view similar to Figure 1, but showing the operating portion of the device in the position it assumes when excessive withdrawals of gas are being made.

Figure 3 is an end elevation, showing the heating chamber.

Figure 4 is a view, partly in elevation and partly in section, of a modified form of the device.

Figure 5 is a horizontal cross-sectional view taken on the line 5—5 of Figure 4.

In the drawings, the numeral 10 designates an elongate cylindrical storage tank which is particularly adapted to be set up above ground for receiving and holding for vaporization liquefied gases, such as butane, propane and the like, and mixtures and combinations thereof. The tank is adapted to be substantially filled with liquefied gas under pressure through a filler pipe 11 having the customary inlet valve 12 at its upper end; and an escape pipe 13, having an outlet valve 14 at its upper end, permits the vaporized gas to flow from the tank as it is filled, preferably into the filling tank truck (not shown) or other supply source. A float gage element 15 extends

downwardly through the escape pipe, in the usual manner, for indicating the liquid level in the tank.

The control system includes a vapor chamber 16 having communication with the vapor space 17 of the storage tank 10 by means of a U-shaped gas conductor member or tube 18. One arm 19 of the gas conductor member communicates with the vapor chamber 16, while the other arm 20 stands upright in alignment with the filler pipe 11, as clearly shown in Figure 1, and communicates with the vapor space 17 of the storage tank. The passageway through the arm 20 is preferably smaller than the passageway through the arm 19, for reasons which will be hereinafter explained.

An elongate conduit 21 extends along the lower portion of the tank 10 and outwardly through one end wall thereof, as clearly shown in Figure 1, and is then directed upwardly along the exterior of the end of the tank to the upper surface, where it extends inwardly to the vapor chamber 16. Upon entering the vapor chamber the conduit 21 is directed upwardly to a point near the upper end of the chamber and is then turned upon itself and extends downwardly in an inverted U-shape to a point near the lower portion of the chamber 16. A portion of the conduit 21 at the end of the tank is subjected to heat and may be enlarged to form a vaporizing section 22.

It will be seen, therefore, that liquefied gas will be conducted through the conduit 21 to the expansion or vaporizing section 22. Since heat is applied at the enlarged expansion section, it will readily be seen that the liquefied gas is converted to the vapor state at that point and is conducted into the vapor chamber 16 in a gaseous form. From the vapor chamber 16, the gaseous gas is conducted through a service line outlet 23 at the upper end of the chamber through the usual fittings attached thereto, such as excess flow valves and cut-off valves 24, and a pressure regulator 25, permitting flow of the gas through the service line to the point of consumption. It will also be seen that the gases in the vapor space 17 of the storage tank have communication with the vapor chamber 16 by means of the gas conductor member 18.

For controlling the flow of gas from the tank, columns of liquefied gas are introduced into the gas conductor member 18 and the liquid conduit 21. As the tank is filled, it will readily be seen that liquefied gas entering the filler pipe 11 will be directed into an enlarged bowl 26 formed at the upper end of the arm 20 of the U-shaped gas conductor member, and will fill said arm 20 to cause overflow thereof. The liquefied gas will be prevented from entering the vaporizing chamber 16 since the valve 24 in the outlet pipe 23 is normally closed during such filling operation, the air or gas trapped in the vaporizing chamber, the conduit 21 and the arm 19 of the conductor 18 preventing such liquefied gas from rising in such members to the same level that it rises in the storage tank. An elongate spiller spout 27 will carry fluid from the bowl 26 to an upright pipe 28 communicating at its lower end with the conduit 21. Therefore, liquefied gas entering the bowl 26 will fill the arm 20 of the U-shaped conductor member 18 and will flow through the spiller 27 into the upright pipe 28, filling it and partly filling the conduit 21. As has already been explained, liquefied gas will not flow through either the U-shaped conductor member 18 or the conduit 21 into the vapor chamber 16, since the

valve 24 in the outlet pipe 23 is normally closed during the filling operation and the trapped air or gas in said conductor member and conduit prevents the liquefied gas from rising through said conductor and conduit to the vaporizing chamber. Also, the liquid gas will fill the tank only to the level of the lower end of the escape pipe 13, any excess liquefied gas flowing out through such escape pipe.

5 The inner end of the conduit 21 is preferably formed with a baffle chamber 29, having an opening 30 provided therein near the bottom of the storage tank 10. A baffle plate 31 having an opening 32 therein is positioned within the chamber 29 between the opening 30 and the lower end of the upright pipe 28. It will be seen, therefore, that the pipe 28 will constantly be filled with liquefied gas to the same level as that in the storage tank 10, since its lower end communicates with the liquefied gas through the opening 30 and its upper end is open to the vapor space 17.

20 A flame or other source of heat 35 may be applied to the vaporizing section 22 of the conduit 21, as illustrated in Figure 1, to cause vaporization of the liquefied gas entering said conduit. A baffle plate 37 may be positioned between the vaporizing section 22 and the end portion of the tank, to prevent radiation of heat from the section 22 to the tank. Also fins (not shown) may 25 be provided on the conduit 21 to reduce conduction of heat therealong. To further preclude heating of the stored liquefied gas, an elongate baffle sleeve 40 surrounds the major portion of the conduit 21 lying at the lower portion of the tank 10. Since liquefied gas can not enter this sleeve, the dead gas space therein will afford insulating qualities. A similar sleeve or cylinder 41 surrounds the arm 19 of the U-shaped conductor member 18 which communicates with the vapor space 16. The sleeve is connected to the tank 10 with a gas-tight joint, and liquefied gas 30 will rise in the annular space between the arm 19 and the sleeve 41 only a portion of the length of the arm 19.

35 45 A closure or housing 45 may be affixed to the tank 10 to enclose and protect the filler pipe, vent pipe, vapor chamber, service outlets and valves connected therewith.

40 In use, the tank 10 is filled or charged by introducing liquefied gas through the valve 12 and filler pipe 11, while permitting displaced vapors in the tank to escape through the vent pipe 13 and check 14, preferably to be returned to the supplying tank truck (not shown). As has been 45 explained, a portion of the liquefied gas will enter the U-shaped conductor member 18 and will overflow from the bowl 26 through the spiller pipe 27 into the upright pipe 28 communicating with the conduit 21 and vaporizing section 22. 50 Since the liquefied gas can not rise materially in the arm 19 of the U-shaped conductor or in the conduit 21 because of the air or gas trapped in the conductor and the conduit when the valve 24 in the outlet pipe 23 is closed, the remainder 55 of the liquefied gas will overflow into the body of the tank to charge it to a predetermined level, ordinarily limited or determined by the position of the lower end of the vent pipe 13. It is to be noted that the liquid body in the tank 10 is precluded from rising to the level of the upper end of the arm 20, whereby such arm always has communication with the vapor space 17 in the tank.

60 Also, when the tank is completely filled, it will be noted that the baffle chamber 29 is completely 65 filled and that the liquefied gas stands in the 70

upright pipe 28 and a substantial height in the conduit 21. When heat is applied to the vaporizing section 22, the liquefied gas therein is vaporized and, if not withdrawn as generated, will force the level of the liquefied gas back along the conduit 21 toward the main storage of the tank 10 through the opening 30.

The gases formed in the vaporizing section and conducted by means of the conduit 21 to the vapor chamber 16, will force the liquefied gas in the conduit 21 back against the higher liquid level of the liquefied gas in the main storage tank 10 because the vapors in the chamber 16 are prevented from returning to the vapor space 17 of the tank 10 by means of the liquid seal provided by the column of liquid standing in the U-shaped conductor member 18. The liquefied gas in the arm 19 will also recede because of the pressure of the gases overhead, thus raising the level of the liquid standing in the arm 20. Since the liquid may rise in the arm 20 to a point above the highest liquid level in the tank 10, the vapor in the chamber 16, communicating with both the arm 19 of the U-shaped gas conductor member and the liquid conduit 21 and applying the same gas pressure against the liquefied columns therein, will force the liquefied gas in the conduit 21 back into the main storage tank 10, through the opening 30, before the liquefied gas in the conductor 18 will be forced out of the upper end of the arm 20.

In normal operations, as the vaporized gas is withdrawn from the chamber 16 through the service outlet, liquefied gas from the storage tank will enter the liquefied gas conduit 21 and flow to the vaporizing section 22, where the applied heat causes rapid vaporization in sufficient quantities to meet normal consumption. During such operations, the vaporized gas in the vapor space 17 of the storage tank is precluded from entering the service outlet by the column of liquid in the U-shaped gas conductor 18.

Under conditions of excessive withdrawal, beyond the capacity of the heating or vaporizing section 22, or in the event the application of heat is discontinued, the supply of vaporized gas entering the chamber 16 through the liquefied gas conduit 21 may not be adequate. The liquefied gas may then rise in the conduit 21 as shown in Figure 2. Due to the relatively small surface exposed to heat of the surrounding medium, the supply of vaporized gas from the conduit 21 will ordinarily not be sufficient to meet normal consumption. In such case, vaporized gas will be withdrawn from the vapor space 17 of the storage tank 10 through the gas conductor 18. As the pressure in the chamber 16 is reduced by withdrawal of vaporized gas, the column of liquid within the U-shaped gas conductor 18 will rise in the arm 19 and fall in the arm 20 to the position shown in Figure 2. When the liquid in the arm 20 has reached the lower end of the erect portion thereof, the vaporized gas from the vapor space 17 may bubble across into the arm 19 and upwardly into the chamber 16, where it will enter the service outlet.

It has already been mentioned that the diameter of the arm 19 is preferably larger than the diameter of the arm 20. This is desirable in order that the height of the column in the arm 19 may never have to rise as high as it would if the arm 19 were the same size as the arm 20, thus reducing the liquid pressure head therein. If desired, however, the two arms may be of the same diameter.

The withdrawal of vaporized gas from the vapor space 17 may continue during the period of abnormal withdrawal, or until the source of heat applied to the vaporizing section 22 is renewed or relighted. When the flame or heat has been reapplied to the vaporizing section 22, or the period of excessive withdrawal has passed, an ample supply of gas will be delivered through the conduit 21 to the chamber 16 to meet normal withdrawal through the outlet 23, and the columns will again resume the positions illustrated in Figure 1.

The provision of the inverted U-shaped portion of the conduit 21 within the chamber 16 is made in order to deliver the vaporized gas in the chamber 16 at a point spaced from the outlet 23 to preclude delivery of heavy or rich gas to the outlet under conditions which would permit condensation of such gas in the service line. Should such heavy or rich gas be delivered to the chamber 16, it may condense in the chamber and fall into the arm 19 of the U-shaped gas conductor 18, adding to the column of liquid therein.

As the column of liquid in the conductor 18 is increased, the liquid will rise in the arm 20 and into the bowl 26 where it will flow through the spiller pipe 27 into the upright member 28 and will be delivered to the baffle chamber 29. Thus, the heavier or rich gases will again be offered into the conduit 21 and vaporizing section 22, where they will be revaporized and again delivered to the chamber 16. In this manner, the heavy or rich gas is reoffered into the chamber 16 for delivery to the service outlet 23 until conditions of temperature are such that the rich gases may flow through the service line without condensation. Also, the liquid column in the conductor is maintained by this condensation process.

A slightly modified form of the invention is illustrated in Figures 4 and 5.

In this form, the U-shaped gas conductor is formed for concentric tubular members, one of which is a depending extension 50 of the vapor chamber 16. A sleeve 51 closely surrounds the lower portion of the chamber and is closed at its lower end. The upper end of the sleeve is formed in an enlarged dish shape, as illustrated at 52. The dish has a spout 53 which is positioned to discharge liquids entering it into the upright conductor 28, communicating with the liquefied gas conduit 21. The cylindrical insulating member 54 is affixed to the under side of the dish 52 and extends downwardly around the sleeve 51, for preventing application of heat to the stored liquids in the tank 10a. The conduit 21, within the chamber 16, instead of being bent upon itself, extends upwardly to the upper portion of the chamber and a concentric or tube sleeve 55 surrounds said conduit and extends downwardly therearound to the lower portion of the vaporizing chamber 16, as clearly shown in Figure 4. The upper end of said tube is secured to the upper end of the chamber with a fluid tight connection, whereby vaporized gas delivered into the chamber through the conduit 21 travels upwardly to the upper end of the conduit and into the tube, whereupon it is directed downwardly to the lower portion of the chamber 16, spaced from the fluid outlet 23.

Other principal parts of the device are generally the same as those previously described and bear the same numerals.

If desired, the entire control assembly just described may be compactly assembled in a short

cylindrical tank section 10a, as illustrated in Figure 4, to provide a compact prefabricated control unit which may be assembled at a factory and shipped to other points for assembly with the balance of a storage tank which will be made at such point. In this manner, the essential control mechanism is constructed and assembled at the factory, where it may be accurately and correctly made to assure proper functioning.

A back-up ring 56 is provided at the open end of the short cylindrical tank portion 10a of the prefabricated unit and may be utilized for attaching the balance of the cylindrical storage tank thereto, by welding in the usual manner.

The functioning of this modified form of the invention is exactly the same as that of the form previously described. A liquid column will stand within the sleeve 51 in the annular space between said sleeve and the lower extended portion 50 of the chamber 16, as well as within the lower portion of said chamber. Thus, a liquid column separating the vapor space within the storage tank from the vapor chamber 16 is provided.

If desired, the fuel for supplying the heat applied to the vaporizing section 22 may be derived from the service outlet line, as shown in Figure 4. A T 57 is connected in the service line, and a gas line 58, having a valve 59 and a burner 60 thereon, is connected to one branch of the T. The other branches are connected to the service line.

It will be seen, therefore, that a control system for liquefied gas storage and dispensing device has been provided, which will in no case permit liquid to enter the service line, but will continue to deliver gas vaporized by the heat absorbed by the main tank of the plant or by the vaporizing section 22. Under conditions of heavy withdrawal, withdrawal over and above the capacity of the vaporizer, gas may be delivered to the service outlet from the vapor space 11 of the tank 10.

It will further be seen that a control system has been provided wherein there are no mechanical seating valve portions or mechanisms. The entire control of the flow of vaporized gas is by means of liquid columns. Further, since the heavy or rich gas which may condense in the chamber 16 is delivered to one arm of the gas conductor 18, the liquid column in such conductor is maintained in adequate volume to control the flow of gas from the vapor space of tank 10 to the chamber 16.

Also, it will be seen that the device provides for reoffering of the heavy or rich gas in vaporized state to the service outlet until temperature conditions are suitable for acceptance of the gas into the service outlet.

Furthermore, since means has been provided for admitting vaporized gas from the vapor space of the storage tank to the vapor chamber 16, liquefied gas will not be delivered to the service outlet.

Also, it will be seen that a system has been provided which is particularly adapted to be assembled as a prefabricated compact component of a complete system at a central point of manufacture, and which may be readily transported to other points for attachment of suitable storage vessels thereto.

It will also readily be seen that the system is particularly adapted for operation above ground and offers a practical system for the use of flame or other applied heat to cause vaporization, but may also be used for under-ground installations.

Furthermore, it is manifest that the system is simple in structure and operation and is especially suitable for complete enclosure for operation without fear of mechanical failure or high maintenance cost.

It will particularly be noted that the baffle chamber 29 provides means for containing the heavy or rich mixture in the conduit 21, in the event of fluctuating demand or withdrawal which may cause liquid in the conduit to be forced toward the tank 10 as the volume of gas in the conduit 21 is increased, thus reducing the possibility of admixture of such heavier mixture with the contents of the tank.

The foregoing description of the invention is explanatory only, and changes in the details of the construction illustrated may be made by those skilled in the art within the scope of the appended claims, without departing from the spirit of the invention.

What I claim and desire to secure by Letters Patent is:

1. A liquefied gas storage and dispensing system including, a storage tank for holding liquefied gas under pressure, a conduit communicating with the lower portion of the tank for withdrawing liquefied gas therefrom and delivering said liquefied gas to a vaporizing section, a service outlet for vaporized gas from said vaporizing section, a conductor having one end communicating with the upper portion of the storage tank and the vaporized gas therein and having its other end communicating with the outlet from the vaporizing section, and means for utilizing a column of liquefied gas in said conductor for normally closing off the flow of vaporized gas through said conductor and for permitting flow of such vaporized gas to the outlet when the level of liquefied gas in the conduit rises to a predetermined level in the vaporizing section, the conduit communicating with the lower portion of the storage tank being provided with means limiting return of liquefied gas from the conduit to the storage tank and a chamber for containing the liquefied gas in the conduit in the event such gas is forced toward the tank by fluctuations in withdrawals from the system, whereby admixture of liquefied gas in the conduit with the contents of the tank is reduced.
2. A compact control system for use with a liquefied gas storage and dispensing system including, a tank end section adapted to be connected with a storage tank for holding liquefied gas under pressure, a conduit communicating with the lower portion of said tank end section and adapted to receive liquefied gas from such section and deliver such liquefied gas to a vaporizing section, an outlet for vaporized gas from said vaporizing section, a conductor having one end communicating with the upper portion of the tank end section and the vaporized gas therein and having its other end communicating with the outlet from the vaporizing section, and means for utilizing a column of liquefied gas from the tank in said conductor for normally closing off the flow of vaporized gas through said conductor and for permitting flow of such vaporized gas to the outlet when the level of liquefied gas in the conduit rises to a predetermined level in the vaporizing section.
3. A liquefied gas storage and dispensing system including, a storage tank for holding liquefied gas under pressure, a conduit communicating with the lower portion of the tank for withdrawing liquefied gas therefrom and delivering said

liquefied gas to a vaporizing section, an outlet from said vaporizing section for vaporized gas, an upright conductor having its upper end communicating with the upper portion of the storage tank and the vaporized gas therein, a second upright conductor having its upper end communicating with the outlet from the vaporizing section, said upright conductors having their lower ends communicating, said conductors providing means for utilizing a column of liquefied gas therein for normally closing off the flow of vaporized gas from the vapor space of the storage tank to the outlet, and for permitting flow of such vaporized gas to the outlet when the level of liquefied gas in the conduit rises to a predetermined level in the vaporizing section.

4. A liquefied gas storage and dispensing system including, a storage tank for holding liquefied gas under pressure, a conduit communicating with the lower portion of the tank for withdrawing liquefied gas therefrom and delivering said liquefied gas to a vaporizing section, a service outlet from said vaporizing section for vaporized gas, a conductor having one end communicating with the upper portion of the storage tank and the vaporized gas therein and having its other end communicating with the outlet from the vaporizing section, means for utilizing a column of liquid in said conductor for normally closing off the flow of vaporized gas through said conductor and for permitting flow of such vaporized gas to the outlet when the volume of liquefied gas in the conduit increases to a predetermined amount in the vaporizing section, and means for conducting excess liquid from the conductor to the conduit at the lower portion of the tank.

5. In a liquefied gas storage and dispensing system having a storage tank for holding liquefied gas under pressure and having a conduit for receiving liquefied gas from the storage tank and vaporizing such gas and delivering vaporized gas to a service outlet, the improvement which includes, a conductor communicating with the vapor space of the storage tank and service outlet, means for utilizing a column of liquid for normally closing off flow of vaporized gas through said conductor and for permitting flow of such vaporized gas to the service outlet when the level of liquefied gas in the conduit rises to a predetermined level, means for preventing delivery of condensed components of the gas from the conduit to the service outlet, and means for conducting such condensed gas to the conduit for re-vaporization and redelivery to the service outlet.

6. In a liquefied gas storage and dispensing system having a storage tank for holding liquefied gas under pressure and a conduit for receiving liquefied gas from a storage tank and for vaporizing such gas and delivering vaporized gas to a service outlet, the improvement which includes, a conductor communicating with the vapor space of the storage tank and with the service outlet, means for utilizing a column of liquid for normally closing off flow of vaporized gas through said conductor from the vapor space of the storage tank to the service outlet and for permitting flow of such vaporized gas from the vapor space of the storage tank to the service outlet when withdrawal of vaporized gas from the conduit exceeds its delivery a predetermined amount, and means for conducting condensed components of the gas from the service outlet to the conductor for maintaining the column of liquid in the conductor.

7. In a liquefied gas storage and dispensing sys-

- tem having a storage tank for holding liquefied gas under pressure and having a conduit for receiving liquefied gas from the storage tank and vaporizing such gas and delivering vaporized gas to a service outlet, the improvement which includes, a conductor communicating with the vapor space of the storage tank and with the service outlet, means for utilizing a column of liquid in said conductor for normally closing off flow of vaporized gas through said conductor and for permitting flow of such vaporized gas to the service outlet when the level of liquefied gas in the conduit rises to a predetermined level, means for preventing delivery of condensed components of the gas from the conduit to the service outlet, and means for delivering such condensed components to the conductor for maintaining the liquid column therein.
8. A liquefied gas storage and dispensing system including, a storage tank for holding liquefied gas under pressure, a conduit communicating with the lower portion of the tank for withdrawing liquefied gas therefrom and delivering said liquefied gas to a vaporizing section, a service outlet from said vaporizing section for vaporized gas, a conductor having one end communicating with the upper portion of the storage tank and the vaporized gas therein and having its other end communicating with the outlet from the vaporizing section, means for utilizing a column of liquid in said conductor for normally closing off the flow of vaporized gas through said conductor and for permitting flow of such vaporized gas to the outlet when the volume of such liquefied gas in the conduit increases to a predetermined amount in the vaporizing section, and means for conducting condensed components of the gas from the service outlet to the conductor for maintaining the column of liquid in the conductor.
9. A liquefied gas storage and dispensing system including, a storage tank for holding liquefied gas under pressure, a conduit communicating with the lower portion of the tank for withdrawing liquefied gas therefrom and delivering said liquefied gas to a vaporizing section, a service outlet from said vaporizing section for vaporized gas, a conductor having one end communicating with the upper portion of the storage tank and the vaporized gas therein and having its other end communicating with the outlet from the vaporizing section, means for utilizing a column of liquid in said conductor for normally closing off the flow of vaporized gas through said conductor and for permitting flow of such vaporized gas to the outlet when the volume of such liquefied gas in the conduit increases to a predetermined amount in the vaporizing section, and means for conducting condensed components of the gas from the service outlet to the conductor for maintaining the column of liquid in the conductor.
10. A liquefied gas storage and dispensing system including, a storage tank for holding liquefied gas under pressure, a conduit communicating with the lower portion of the tank for withdrawing liquefied gas therefrom and delivering said liquefied gas to a vaporizing section, a service outlet from said vaporizing section for vaporized gas, a conductor having one end communicating with the upper portion of the storage tank and the vaporized gas therein and having its other end communicating with the outlet from the vaporizing section, means for utilizing a column of liquid in said conductor for normally closing off the flow of vaporized gas through said conductor and for permitting flow of such vaporized gas to the outlet when the volume of such liquefied gas in the conduit increases to a predetermined amount in the vaporizing section, and means for conducting condensed components of the gas from the service outlet to the conductor for maintaining the column of liquid in the conductor.
11. The outlet when the volume of such liquefied gas in the conduit increases to a predetermined amount in the vaporizing section, means for maintaining the column of liquefied gas in the conductor, and means for conducting excess liquid from the conductor to the conduit at the lower portion of the tank.
